[57] CLAIM

The ornamental design for a spatula for use in playing a game, substantially as shown and as described.

DESCRIPTION

FIG. 1 is a plan view of my design for a spatula for use in playing a game;

FIG. 2 is a side elevation, the opposite side being similar in appearance;

FIG. 3 is an end elevation in the direction of the arrow 3 in FIG. 1;

FIG. 4 is an underneath plan view;

FIG. 5 is a longitudinal section taken on the line 5—5 in FIG. 1 looking in the direction of the arrows; and

FIG. 6 is an end elevation in the direction of the arrow 6 in FIG. 1.

FIG. 1

FIG. 3
